(57) **CLAIM**

(22) Filed: **Dec. 24, 2008**

The ornamental design for a golf club head, as shown and described.

(51) LOC (9) Cl. **21-02**

DESCRIPTION

(52) U.S. Cl. **D21/759**

FIG. 1 is a rear bottom perspective view of a golf club head embodying the inventive design.

(58) Field of Classification Search **D21/747-751,**
D21/759; 473/324-331, 350

FIG. 2 is front perspective view thereof.

See application file for complete search history.

FIG. 3 is a top perspective view thereof.

(56) **References Cited**

FIG. 4 is a bottom perspective view thereof.

U.S. PATENT DOCUMENTS

FIG. 5 is a toe-side elevational view thereof.
